UNITED STATES PATENT OFFICE.

HARRISON H. EATON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

RESURFACING DEVICE.

1,329,383.

Specification of Letters Patent.

Patented Feb. 3, 1920.

Application filed August 13, 1915. Serial No. 45,416.

To all whom it may concern:

Be it known that I, HARRISON H. EATON, a citizen of the United States, residing at Beverly, in the county of Essex and State of Massachusetts, have invented certain Improvements in Resurfacing Devices, of which the following description, in connection with the accompanying drawings, is a specification, like reference characters on the drawings indicating like parts in the several figures.

This invention relates to devices for use in forming smooth surfaces upon articles of wood or like material; and a particular object of the invention is to provide an improved device of this character adapted for use in planing the working surfaces of the cutting blocks of die cutting machines, such, for example, as the so-called "clicking" machine which is used extensively for dieing out uppers in the manufacture of boots and shoes.

These blocks are subject to considerable wear through contact with the cutting edges of the dies, and since it is essential for the best results that the block shall present a comparatively smooth working surface, frequent resurfacing of the block is necessary. Such blocks, however, are usually made of hard and resistant material, and when made of wood have a working surface which is transverse to the grain of the wood. For this reason it has been found very difficult to resurface a block by the use of hand tools or while the block is in place in the machine, and it has been a common practice to remove the block entirely from the cutting machine and resurface it in a planing machine especially provided for the purpose.

An important object of this invention is to avoid the loss of time spent in removing and replacing the cutting blocks of die cutting machines, as well as a large part of the expense of planing machines such as have been frequently required heretofore for resurfacing the blocks, and to provide a resurfacing device of relatively inexpensive character which may be used to plane the working surface of a cutting block while the block is in place in the machine.

It is, moreover, a well known fact that in the operation of a clicking machine, constructed as shown, for example, in the United States Patent to Bates, No. 921,503,

granted May 11, 1909, the presser member, 55 which projects forwardly over the block from a vertically reciprocating post at the rear of the block and swings about the axis of the post to different positions over the block, is less positive in its action when it 60 strikes a die with its outer end portion than it is when the die is engaged by portions of the presser member nearer the operating post. This results from different causes, among which are the wear of the post in its 65 bearings, the inertia of the presser member, and the tendency of the frame and other portions of the machine, however strongly constructed, to spring slightly upon an operating stroke of the presser member. With 70 the object of remedying this difficulty it is frequently the practice to raise slightly the front portion of the block so that the cutting surface of the block may slope toward the rear; but even with this arrangement 75 the best results may not be secured when the presser member is swung so as to project toward the side of the block. Maximum efficiency under all conditions would require a gradual slope of the cutting surface of the 80 block, not only from the front but also from both sides toward that portion of the block which is in the vicinity of the post. Such a result it is not possible to obtain by means of planing machines such as are frequently 85 used for resurfacing cutting blocks, nor have hand manipulated tools such as heretofore devised been found entirely practicable for use in forming a cutting surface of the desired contour. It is accordingly a further 90 important object of this invention to provide a resurfacing device which may be readily manipulated and controlled to vary as desired the contour of the surface of a cutting block.

To the above and other ends an important feature of the invention consists in a novel organization of mechanism arranged to provide a device which may be moved by hand over the surface of the work and including 100 a power driven tool constructed and arranged for effective operation upon the work with the expenditure of but little power and for convenient control to vary its effective engagement with the work.

The above and other features of the invention, including certain details of construction and combinations of parts, will

now be described with reference to the accompanying drawings, which illustrate a preferred embodiment of the invention, and will be pointed out in the claims.

5 In the drawings,—

Figure 1 is a perspective view of a device in which the invention is embodied;

Fig. 2 is a view of the device in side elevation and partly in vertical section;

10 Fig. 3 is a perspective view, with portions broken away, illustrating the relation of the operating tool to other elements of the structure;

Fig. 4 shows the operating tool detached;

15 Fig. 5 illustrates the application of an alternative form of cutting member to the operating tool;

Fig. 6 is a section through a portion of the tool, illustrating in greater detail the 20 preferred form of cutting member shown in Fig. 4, and

Fig. 7 is a fragmentary view illustrating the attachment of the waste receptacle to other portions of the device.

25 The device includes a supporting member or base 2 having a lower, plane work engaging face of extended area for guiding the device in its movements over the surface of the work, and a handle 4 whereby the device 30 may be manipulated. Secured to the member 2 is a standard 6 upon which may be mounted, as shown, an electric motor 8 with the motor shaft 10 extending downwardly in substantially perpendicular relation to the plane of the work engaging face 35 of the member 2, a plate 12 on the standard providing a lower bearing for the shaft. The motor may be of any suitable size or type, and is to be supplied with current from any convenient source through a flexible conduit 14.

The member 2 is provided in its work engaging face with a substantially circular opening in the form of a recess 16 in which 45 is mounted for rotation in a plane substantially parallel to the plane of said face a tool 18 having oppositely extending arms 20 and 22 formed respectively to carry different types of cutters or the like for operating upon the surface of the work. Preferably only one cutter will be used at a time, and the form which has been found most generally satisfactory in use is illustrated in Figs. 4 and 6 and comprises a circular disk 55 24 having a peripheral cutting edge and substantially frusto-conical in shape. This cutter is detachably and adjustably mounted upon a pin 26 at the forward end of a recess 28 cut in the lower face of the arm 20, the recess conforming to the shape of the upper face of the cutter, and the recess and the pin coöperating to position the cutter in a plane oblique to the plane of rotation of the tool with the edge of the cutter projecting downwardly and forwardly from

the front side of the arm 20. A clamp member 30 secured in the recess 28 by means of a screw 32 serves to maintain the cutter securely in place, and upon loosening the screw the cutter may be turned to bring different portions of its cutting edge into working position.

70 The form of cutter shown in Figs. 4 and 6 has been found particularly satisfactory in operation upon the hard and resistant material of the cutting blocks of die cutting machines, since by reason of the curved edge of the cutter it makes, for the most part, a shearing cut which is especially advantageous in cutting across the grain of wood and contributes materially to the formation of a smooth finished surface. This cutter, moreover, is readily adjustable, so that when one portion of its cutting edge has become dull, another portion may be 80 brought quickly into operative position. In Fig. 5 is shown a different form of cutter which may be used, if desired, instead of the cutter 24. This cutter is adapted to be secured to the arm 22 of the tool and comprises a plate 34 from which project a pair of saw teeth 36. Since these teeth are alined in the direction of the cut and since they present a smaller extent of operative engagement with the work than a cutter 95 such as 24, it will be apparent that less power will be required to drive the tool when this form of cutter is in use. For this reason a cutter of the form shown in Fig. 5 may be found preferable under certain conditions. Under most conditions, however, the cutter 24 will be preferred, particularly because of the smoothness of its cut and its ready adjustability. The cutter mechanism disclosed in Figs. 4 and 6 is 100 not claimed herein but is made the subject matter of a divisional application, Serial No. 328,014, filed October 2, 1919.

105 The means whereby the tool 18 is mounted to be driven from the shaft 10 comprises a sleeve 38 on the tool encircling the end portion of the shaft and splined to the shaft by a key 40. Threaded upon the upper end of the sleeve are a pair of nuts 42, and loosely encircling the sleeve between these nuts and a ball bearing 44 is a collar 46 having pins 48 that project from its opposite sides through vertical slots 50 formed in a substantially cylindrical portion 52 of the member 2, which embraces the collar 46. The pins 48 are supported in the forked end of a lever 54 which is pivoted on the member 52 at 56 and extends rearwardly toward the handle 4. The lever 54 thus serves to support the collar 46 and through the collar the tool 18, and forms a portion of the adjusting means for the tool whereby the tool is raised or lowered to vary the extent of projection of the cutter toward the work. A spring 58 mounted in a socket in the stand- 115 120 125 130

ard 6 presses upon the lever 54 and tends normally to elevate the tool out of contact with the work. In order to enable the operator to control readily the extent of projection of the tool toward the work in accordance with differences in operating conditions and to vary the depth of the cut, a lever 60 is pivoted adjacent to the handle 4 and has an arm 62 projecting under the rear end of the lever 54, so that by pressure upon the lever 60 while manipulating the device by the handle the operator may variably control the effect of the tool upon the work. The construction shown is particularly effective in positively pressing the tool against the work, the arm 62 of the lever 60 being so arranged as to exert a crowding action upon the extremity of the lever 54 which enables the operator to control the tool much more efficiently than is possible with previously existing constructions. An adjustable stop 64 serves by engagement with the lever 54 to limit the depression of the tool. This stop is not an ordinary set screw but is a member provided with a knurled head so that it may be readily adjusted by one finger of the operator's hand which grasps the handle 4, as the tool is being moved back and forth across the work. When the cutting block or other work which is being resurfaced presents marked irregularities, the amount of projection of the cutter disk from the level of the work engaging surface of the member 2, in order to obtain desirable results, will be less over some areas and greater over closely adjacent areas. It is important, therefore, that the adjustable stop 64 be accessible and readily operable to enable the operator to control positively the projection of the cutter disk when the conditions call for relatively frequent and prompt adjustments of the cutting means. In case a given surface is to be cut down a predetermined uniform amount the adjustable stop 64 may be secured fixedly in desired position by the clamping effect produced by turning the screw 64 in the proper direction.

In order that the tool may operate effectively, it is necessary to prevent the waste material detached from the surface of the work from accumulating in the recess 16. To this end the recess is provided with a tangential outlet seen at 66, Fig. 3, and in the operation of the tool the arms 20 and 55 22 serve as fans to create in the recess 16 an air current which escapes through the outlet 66 and carries the waste material with it. Air is admitted to the recess on the side opposite to the work through openings 68 in the member 52. For the purpose of increasing the force of the air current, the tool 18 carries between the arms 20 and 22 additional fan blades 70.

In order to prevent the waste material 65 from accumulating upon the surface of the

work or from flying about the room, the device is provided with a receptacle 72, and a conduit 74 leads from the outlet 68 to this receptacle. The receptacle is preferably formed as a sheet metal box, and is provided in its top with a large number of openings 76 of sufficient size to permit the escape of air but small enough substantially to prevent the escape of the waste particles. The receptacle 72 is so mounted as to be retained securely in position during the operation of the device, and at the same time to be readily detachable to permit it to be emptied. For this purpose one end of the receptacle is provided with an opening 78 to receive the delivery end of the conduit 74 which is spaced slightly from the member 2, and near its other end the receptacle is provided with a lug 80 which hooks over a flange at the side of the member 2. In order to detach the receptacle it is therefore necessary only to raise its rear end and slide it rearwardly to disengage it from the conduit 74. It may then be emptied by removing its cover 82.

To facilitate the manipulation of the device, a second handle 84 is provided, this handle projecting laterally from the side of the standard 6 adjacent to the motor 8.

In the light of the preceding description, a detailed explanation of the operation of the device will be unnecessary. The conduit 14 having been connected to any convenient source of electrical current and the current turned on, the tool is continuously driven, and the device is moved by the operator 100 slowly over the work in any desired direction to cause it to operate upon the surface to be finished. The extent of engagement of the cutter with the work is controlled at will by pressure upon the lever 60 and by such 105 control the tool may be caused, if desired, to cut progressively deeper during a forward movement of the device. Before retracting the device at the end of a forward movement the lever 60 may be released, if 110 desired, to permit the tool to be withdrawn from engagement with the work. The waste material, as fast as it is detached by the cutter, is carried by the air current through the conduit 74 into the receptacle 72, and 115 when the receptacle is full it may be readily detached and emptied.

The arrangement whereby the tool is caused to rotate in a plane substantially parallel to the surface of the work contributes materially, as will be evident, to simplicity of construction of the device and convenience of control of the tool while permitting the tool to be driven directly from the motor shaft. This arrangement also has 120 the additional advantage, especially in a device for use in resurfacing cutting blocks, that the tool is caused to cut directly across the grain of the wood. This contributes materially to the effectiveness of the tool and 130

to the formation of a smooth surface on the work.

Although the device embodying the invention has been described as of particular utility for resurfacing the cutting blocks of die cutting machines, it should be understood that it is by no means limited to this particular use. Except as required, moreover, by the express terms of the claims the invention is not to be regarded as limited to constructional details of the form herein shown and described.

Having described the invention, what I claim as new and desire to secure by Letters 15 Patent of the United States is:—

1. A device of the class described comprising, in combination, a supporting member having a plane work engaging face to guide the device in movements over the work 20 and an opening in said face, a motor mounted on said member and having a shaft extending in substantially perpendicular relation to the plane of said face, a tool in said opening splined on the motor shaft to 25 be freely slidable longitudinally of the shaft, a member arranged to support the tool, means arranged to engage the member for enabling the operator to press down the tool progressively as he moves the device 30 over the work, and means controllable during operation of the tool to determine positively the extent of maximum depression of the tool during operation thereof.

2. A device of the class described comprising, in combination, a supporting member having a work engaging face to guide the device by sliding movement over the work and an opening in said face, a substantially upright handle on said member for 35 use in moving the device over the work, a cutting tool mounted for rotation in said opening, means to determine adjustably the

extent of maximum projection of the tool below said work engaging face, said means being located accessibly adjacent to said handle, means for elevating the tool normally above the plane of said face, and controlling means connected to the tool and extending to a position in front of said handle to be grasped with the handle to enable the operator to force the tool beyond said face and thereby vary the depth of the cut during movement of the device over the work.

3. A device of the class described comprising, in combination, a supporting member having a work engaging face to guide the device in movements over the work, a cutting tool mounted slidably on said member for rotation in a plane substantially parallel to the plane of said face, a lever 60 mounted on said member and arranged to support the tool, resilient means arranged to operate upon said lever to elevate the tool, means for operating said lever to depress the tool, and a stop controllable while 65 the tool is in operation for limiting adjustably the extent of depression of the tool.

4. A device of the class described comprising, in combination, a supporting member having a work engaging face to guide the device in movements over the work, a handle on said member for use in moving the device over the work, a cutting tool mounted on said member for rotation in a plane substantially parallel to the plane of 75 said work engaging face, a lever mounted on the member and arranged to support the tool, and a second lever arranged to exert a crowding action upon said first named lever positively to depress the tool and hold it 80 firmly in contact with the work.

In testimony whereof I have signed my name to this specification.

HARRISON H. EATON.
